(57) **CLAIM**

The ornamental design for a golf shoe, as shown and described.

DESCRIPTION

FIG. 1 is a top perspective view of the golf shoe showing our new design;

FIG. 2 is a front elevation view thereof;

FIG. 3 is a right side elevation view thereof;

FIG. 4 is a bottom plan view thereof;

FIG. 5 is a top plan view thereof;

FIG. 6 is a left side elevation view thereof;

FIG. 7 is a rear elevation view thereof; and,

FIG. 8 is a bottom perspective view thereof.

In FIGS. 1–8, the double row of broken lines on the golf shoe represent stitching that forms part of the claimed design. All other broken lines illustrate portions of the golf shoe that form no part of the claimed design.
